CLAIM

The ornamental design for a loudspeaker, substantially as shown and described.

DESCRIPTION

FIG. 1 is a top, front, side perspective view of a loudspeaker showing the claimed design;

FIG. 2 is a front view thereof;

FIG. 3 is a back view thereof;

FIG. 4 is a top view thereof;

FIG. 5 is a bottom view thereof;

FIG. 6 is a side view thereof; and,

FIG. 7 is an opposite side view thereof.

The broken lines in the figures illustrate the portions of the design that form no part of the claimed design.
